ZERO PRINTING CONTROL MECHANISM

Heinrich Konrad Friedrich Ewald, Chemnitz,
Germany, assignor to Wanderer-Werke Aktien-
gesellschaft, Siegmar-Schönau, Germany

Original application September 3, 1935, Serial No.
39,065. Divided and this application Septem-
ber 23, 1940, Serial No. 357,988. In Germany
September 7, 1934

4 Claims. (Cl. 101—93)

This invention relates to improvements in printing calculating machines and particularly to mechanisms therein for the interruption of automatic zero printing, including pawls automatically operated by stops and disposed on the paper carriage.

The primary object of the invention is to provide a compact mechanism for this purpose that will be reliable in operation.

According to the present invention the parts operated by the stops on the paper carriage are kept retracted, during the travel of the paper carriage, out of the range of action of the stops, and are released for co-operation with the stops at a suitable time during a machine operation.

A constructional example of the mechanism according to the invention is illustrated in the accompanying drawing in which:

Figure 1 is an elevation showing the printing mechanism of a calculating machine equipped with the invention;

Fig. 2 is a plan of the parts which controls zero printing;

Fig. 3 is a plan view of a part of the paper carriage, and

Fig. 4 shows a stop for controlling zero printing.

The printing mechanism illustrated comprises the usual type carriers 1 connected to the rack sectors 2 of the calculating machine, which rack sectors have bent portions 3 at the upper ends. The platen roller 4 is mounted in the paper carriage 5 which is slideable in guides 6 on the machine frame 6a. During printing the hammers 7 under the action of springs 8 impel the type carriers 1 against the platen 4. The printing hammers 7 are held in position of rest by locking pawls 9 which are acted upon by springs 10. The locking pawls 9 are in the form of two armed levers and have pivoted at their free ends hook members 11 acted upon by springs 12 which tend to hold them below lugs 13 of the locking pawls 9. The arrangement is such that the hook member 11 of each pawl 9 lies under the lug 13 of the adjacent pawl 9 assigned to the next lower ordinal place, Fig. 2.

To return the hammers 7 to initial position after printing there is provided a yoke 14 which is actuated by a push rod 15 in the course of a machine operation. The push rod 15 has a forked end guided by a pin 16 provided on a disk 17. The disk 17 is fixed on a shaft 18 connected by links 36, 37, 38 to the main operating shaft 39 of the machine, and the disk 17 performs a to and fro rocking movement during each oscillation of the main shaft 39. The shaft 18 has a second

disk 19 fixed thereto, Fig. 2. The disks 17 and 19 are connected to each other by means of a round bar 20 on which hammer releasing pawls 21 are pivotally mounted, which pawls are under the action of the tension springs 22. The free ends of the tension springs are attached to a rod 23 which is attached between the disks 17 and 18. The lower ends of the release pawls 21 extend below the lugs 3 of the rack sectors 2 and are held by the latter normally out of engagement with the lugs 13 of the locking pawls 9. When a digit is set up in one ordinal place on the calculating machine, the lug 3 of the corresponding rack sector 2 frees the release pawl 21 assigned to this ordinal place whereby the latter moves under the action of its spring 22.

A comb 24 is fixed between the disks 17 and 19, between the teeth of which are guided push rods 25 which are jointed to bell cranks 26 and cooperate with the free ends of the release pawls 21. The bell cranks 26 are pivoted on a rod 27, on which are fixed two cranks 28 which together with a rod 29 extending between them, form a yoke which serves for the simultaneous operation of all the push rods 25, by rocking all the bell cranks 26. This rocking movement of the yoke 28, 29 is effected by a crank 30 which cooperates with a cam disk 31, the latter being connected, as shown in Figure 1, by means of a link 40 to the main shaft 39 of the machine.

Opposite the free ends of the bell cranks 26 there is arranged a stop 32 exchangeably mounted on a bar 33. This bar is inserted in aligned slots of a frame 34 disposed in a suitable opening 35 of the base plate of the paper carriage 25 and attached by screws 35. A stop 32, as shown in Figure 4, has three downwardly extending projections.

The operation of the above described printing mechanism is as follows:

At the beginning of a machine operation the parts of the printing mechanism lie in a position differing from that shown in Figure 1 in that the parts connected through links 36, 37, 38 and 40 to the main shaft 39 of the machine occupy position somewhat displaced in counter-clockwise direction to that illustrated, the cam disk 31 being in such a position that the pin of the crank 30 lies on the part of the cam which is of maximum diameter. The rising of the pin of the crank 30 causes the yoke 28, 29 to be forced against the lower arms of the bell cranks 26, and the upper arms of the bell cranks 26 are retracted from the range of action of the stop 32. The push rods

25 are thus drawn to the left and their action on the free ends of the release pawls 11 has retracted these against the action of the springs 12. Consequently the shaft 18 and disks 17 and 19 fixed thereto, as well as the parts carried thereby, occupy a position somewhat displaced in anti-clockwise direction relatively to that shown in Figure 1.

During a machine operation the links 36, 37, 38, 40 are drawn to the left in the forward stroke 10 of the main shaft 39. This brings the cam disk 31 into the position shown in Figure 1, and while the pin of the link 30 slides on the smaller-diameter portion of the cam disk 31, the bell cranks 26 are released to cooperate with the stop 32. The upper arms of the bell cranks 26 thus may 15 contact with the stop 32 and unless they encounter a downwardly extending projection of the stop 32, they arrive at the position shown in Figure 1. However, those bell cranks 26 which encounter extensions on the stop 32 are prevented from further upward movement, and their push rods 25 hold the associate release pawls 11 out of engagement with the lugs 13 of the pawls 9. As a result, at those places in the printing mechanism at which there are downwardly projecting extensions on the stop 32, there is an interruption of zero printing, since the movement 20 of the pawls 9 which release the printing hammers 7 is interrupted by the retraction of the corresponding release pawls 11.

At the same time the shaft 18 performs a rotary movement in clockwise direction whereby the round bar 20 between the disks 17 and 19, and the hook members 21 thereon will swing upwardly. Since the pawls 21 have their lower ends extending below the lugs 3 of the rack sectors 2 only those hook members 21 engage behind the lugs 13 of the pawls 9, which have been released by the lugs 3, of rack sectors that have been swung upwardly corresponding to digital values of operated keys. If for example in a calculating machine with ten ordinal places, a digit has been set up in the sixth place, the sixth rack sector 2 will move up and release the sixth hook member 21. The latter lies behind the lug 13 on the sixth pawl 9, and during the rotary movement of the disk 17 and 19 incidental to the forward stroke of the main shaft of the machine, this sixth pawl 9 is moved out of its locking position whereby also the sixth printing hammer 7 is released. The release pawl 11 of the sixth locking pawl 9 carries with it the fifth pawl 9 and hereby releases the fifth printing hammer 7. The release pawl 11 of the fifth locking pawl 9 in turn carries with it the fourth pawl 9, and so on. Thereby all the printing hammers 7 of the lower ordinal places are released.

By means of the stop 32, as above explained, one release pawl 11 may be made inoperative at any desired place, so that from this place downwardly the further operation of the pawls 9 is prevented. For example if in a ten ordinal place calculating machine the release pawl 11 between the fifth and fourth place is made inoperative, then in the printing operation, if a digit has been set up in the sixth place, only the printing hammer for the sixth place and that for the fifth place will be released.

After printing is completed the links 36, 37, 38, 40 are restored to the right during the return stroke of the machine shaft 39. In this movement the crank 30 slides again on the largest diameter part of the cam disk 31 and by means of the yoke 28, 29 rocks the bell cranks 26 out

5 of the range of action on the stop 32. Meanwhile the shaft 18 and the parts fixed thereto have returned to their initial position in which operation the pin 16 of the disk 17 forces back the push rod 15 whereby the printing hammers 7 are returned by the yoke 14 into their position of rest.

By use of stops 32 having extensions provided at different places it is possible to interrupt automatic printing at any desired places.

In the mechanism according to the invention the contact ends of the bell cranks 26 are arranged in a plane lying in the direction of the paper carriage movement. This makes it possible to make the stop 32 for controlling zero printing in the form of a thin plate the dimensions of which in the direction of the paper carriage movement can be kept comparatively small. By arranging the bell cranks 26 as close as possible to each other, that is with a smaller pitch than that of the members of the printing mechanism, a more compact arrangement is obtained. This is possible because the bell cranks 26 cooperate with the carrier pawls not directly but through push rods 25. The invention thus has the advantage that the parts for controlling the automatic zero printing on the paper carriage are exceptionally compact without affecting the reliability of operation.

30 The present application is a division of my co-pending application Serial No. 39,065, filed September 3, 1935.

I claim as my invention:

1. In a bookkeeping or calculating machine the combination of a machine frame, a paper carriage slidably arranged on the machine frame, a main drive shaft, a plurality of type-carriers, a plurality of printing-hammers for engaging the type-carriers, a plurality of springs for actuating the printing-hammers, a plurality of locking members for holding the printing-hammers in their position of rest against the action of the springs, a plurality of controllable means for releasing the printing-hammers each releasing means being controlled in dependence upon the position of its corresponding type-carrier, intermediate members actuated by the main drive shaft for actuating the releasing means, a plurality of coupling members each coupling member being pivotally connected to a locking member and coupling the same to the adjacent locking member for effecting automatic zero printing, a plurality of additional springs each of which forces one of the coupling members to its coupling position, a plurality of settable members each settable member controlling one of the coupling members for interrupting automatic zero printing against the action of the corresponding second-named spring, a device for setting simultaneously all the settable members to their position of interrupting zero printing, a member arranged on the paper carriage and having at least one projecting portion for retaining at least one settable member in its position of interrupting zero printing, a cam-like device actuated by the main drive shaft for moving the said setting device in such a manner that during the forward stroke of the cam-like device during a printing cycle certain of the settable members are released to their automatic zero printing position under control of the projecting portions of the said member and during the return stroke of the cam-like device after the printing cycle the settable members are again set to their zero printing interrupting position.

2. In a bookkeeping or calculating machine the combination of a machine frame, a paper carriage slidably arranged on the machine frame, a main drive shaft, a plurality of type-carriers, a plurality of printing-hammers for engaging the type-carriers, a plurality of springs for actuating the printing-hammers, a plurality of locking members for holding the printing-hammers in their position of rest against the action of the springs, a plurality of controllable releasing means for releasing the printing-hammers each releasing means being controlled in dependence upon the position of its corresponding type-carrier, intermediate members actuated by the main drive shaft for actuating the releasing means, a plurality of hooks each hook being pivotally connected to a locking member and coupling the same to the adjacent locking member for effecting automatic zero printing, a plurality of additional springs each of which forces one of the hooks to its coupling position, a plurality of rods each rod controlling one of the hooks for interrupting automatic zero printing against the action of the corresponding second-named spring, a plurality of double-armed levers rotatably arranged in the machine frame each of them being connected with one of the rods, a device for setting simultaneously all the double-armed levers to a position in which the rods are in their zero printing interrupting position, a member arranged on the paper carriage and having at least one projecting portion for retaining at least one double-armed lever in a position in which its corresponding rod is in the zero printing interrupting position, a cam-like device actuated by the main drive shaft for moving the said setting device in such a manner that during the forward stroke of the cam-like device during a printing cycle certain of the rods are released to their automatic zero printing position under control of the projecting portions of the said member and during the return stroke of the cam-like device after the printing cycle the rods are again set to their zero printing interrupting position.

3. In a bookkeeping or calculating machine the combination of a machine frame, a paper carriage slidably arranged on the machine frame, a main drive shaft, a plurality of type-carriers, a plurality of printing-hammers for engaging the type-carriers, a plurality of springs for actuating the printing-hammers, a plurality of pawls for holding the printing-hammers in their position of rest against the action of the springs, a plurality of controllable means for releasing the printing-hammers each releasing means being controlled in dependence upon the position of its corresponding type-carrier, intermediate members actuated by the main drive shaft for actuating the releasing means, a plurality of hooks each hook being pivotally connected to a pawl and coupling the same to the adjacent pawl for effecting automatic zero printing, a plurality of additional springs each of which forces one of the hooks to its coupling position, a plurality of rods each rod controlling one of the hooks for interrupting automatic zero printing against the action of the corresponding second-named spring, a shaft arranged in the machine frame,

a plurality of double-armed levers rotatably mounted on the shaft, each of the double-armed levers being connected with one of the rods, a device for setting simultaneously all the double-armed levers to a position in which the rods are in their zero printing interrupting position, a member arranged on the paper carriage and having at least one projecting portion for retaining at least one double-armed lever in a position in which its corresponding rod is in the zero printing interrupting position, a cam-like device actuated by the main drive shaft for moving the said setting device in such a manner that during the forward stroke of the cam-like device during a printing cycle certain of the rods are released to their automatic zero printing position under control of the projecting portions of the said member and during the return stroke of the cam-like device after the printing cycle the rods are again set to their zero printing interrupting position.

4. In a calculating or bookkeeping machine the combination of a machine frame, a paper carriage slidably arranged on the machine frame, a main drive shaft, a plurality of type-carriers, a plurality of printing-hammers for engaging the type-carriers, a plurality of springs for actuating the printing-hammers, a plurality of pawls for holding the printing-hammers in their position of rest against the action of the springs, a plurality of controllable latches each of them being adapted to act upon one of the pawls for releasing one of the printing-hammers each latch being controlled in dependence upon the position of its corresponding type-carrier, intermediate members actuated by the main drive shaft for actuating the latches, a plurality of hooks each hook being pivotally connected to a pawl and coupling the same to the adjacent pawl for effecting automatic zero printing, a plurality of additional springs each of which forces one of the hooks to its coupling position, a plurality of rods each rod controlling one of the hooks for interrupting automatic zero printing against the action of the corresponding second-named spring, a shaft arranged in the machine frame, a plurality of double-armed levers rotatably mounted on the shaft, each of the double-armed levers being connected with one of the rods, a yoke rotatably arranged on the shaft for setting simultaneously all the double-armed levers to a position in which the rods are in their zero printing interrupting position, a member arranged on the paper carriage and having at least one projecting portion for retaining at least one double-armed lever in a position in which its corresponding rod is in the zero printing interrupting position, a cam-disk actuated by the main drive shaft for moving the yoke in such a manner that during the forward stroke of the cam-like device during a printing cycle certain of the rods are released to their automatic zero printing position under control of the projecting portions of the said member and during the return stroke of the cam-like device after the printing cycle the rods are again set to their zero printing interrupting position.

HEINRICH KONRAD FRIEDRICH EWALD.
